(57) **CLAIM**

The ornamental design for a panel gate frame insert as shown and described.

DESCRIPTION

FIG. 1 is a perspective view of a panel gate frame insert, showing my new design;

FIG. 2 is the front view of the panel gate frame insert of FIG. 1;

FIG. 3 is a back view of the panel gate frame insert of FIG. 1;

FIG. 4 is a side view of the panel gate frame insert of FIG. 1;

FIG. 5 is the other side view of the panel gate frame insert of FIG. 1;

FIG. 6 is a top view of the panel gate frame insert of FIG. 1; and,

FIG. 7 is bottom view of the panel gate frame insert of FIG. 1.

The broken lines in the drawings depicting environment of a gate and hinge form no part of the claimed design.
